SELF STARTING GASEOUS ELECTRIC
DISCHARGE DEVICE

James A. St. Louis, Montclair, N. J., assignor to
General Electric Vapor Lamp Company, Ho-
boken, N. J., a corporation of New Jersey

Application November 22, 1933, Serial No. 699,264

14 Claims. (Cl. 176—122)

The present invention relates to gaseous electric discharge devices in general, and in particular to metallic vapor devices.

A particular object of the invention is to provide a high efficiency light source. Another object of the invention is to provide a metallic vapor arc which is exceptionally stable in operation. Another object of my invention is to provide a metallic vapor arc device which will operate at a relatively high pressure. Another object of my invention is to provide a metallic vapor discharge device whose electrical characteristics will remain constant throughout an appreciable range of vapor temperature. Another object of my invention is to provide a gaseous discharge device which will start without the use of high voltage or auxiliary apparatus. A further object of my invention is to provide an electrode for a gaseous discharge device which is simple in construction and which will have a long useful life. Still other objects and advantages of my invention will appear from the following detailed specification, or from an inspection of the accompanying drawing.

The invention consists in the new and novel structure and combination of elements which is hereinafter set forth and claimed.

As heretofore operated metallic vapor discharge devices have always had an excess of metal present, this excess metal ordinarily comprising a pool in the coolest part of the discharge device. When so operated these devices have had the inherent fault that any change in the temperature of this pool, whether due to changes in the ambient temperature or to changes in the electrical input, has caused a disproportionately large change in the vapor density within the discharge device. This change in vapor density in turn causes a great change in the voltage required to maintain the discharge. Thus in a mercury vapor arc device even a slight drop in the temperature of the pool so decreases the voltage of the arc that the luminous efficiency of the device is greatly impaired, while a slight increase in temperature may make it impossible for the discharge to operate at the available voltage. As a result it has not been practicable heretofore either to build a vapor discharge device which would operate with given electrical characteristics regardless of normal variations in ambient temperature, or to operate one of these devices with the maximum vapor density consistent with continuous operation on a given line potential, despite the fact that the highest efficiency is attainable only with this higher vapor density. It has recently been proposed, however, to overcome these difficulties by

so limiting the available metal that it will all be vaporized when the discharge device is in operation. When such a device is normally operated at a temperature above that at which the metal is all evaporated it is obvious that the vapor will be superheated, but that the density thereof will not vary with temperature in this superheated range. Thus the voltage drop in these devices is no longer responsive to temperature changes within this superheated vapor range. The production of such a device has involved many difficulties, however, especially where it is desired that the device should operate at a high pressure, as in a mercury vapor arc. For example, for a mercury vapor arc to operate with a vapor density corresponding to that of mercury at atmospheric pressure it is necessary that the coolest part of the envelope be maintained at a minimum temperature of 357° C., and in order to insure that a possible decrease in ambient temperature will not result in a reduction in this density it is usually desirable to normally maintain an even higher temperature at this point. In the usual discharge device, as heretofore constructed, wherein there is a great variation in temperature between the different parts of the envelope, this would mean that the hottest portion of the envelope would be at a temperature far above the softening and gas evolving point of any of the available glasses, so that the extremely expensive fused silica would have to be employed. I have discovered that by making several radical changes in the lamp construction the entire envelope may be made to operate at a much more uniform temperature, with the result that any of the harder glasses, such as "pyrex", "nonex", or the like, may be employed for the first time for the envelope of a lamp operating with a minimum temperature at the coolest point which is well above 357° C. One of these changes which I have found to be necessary is the relocation of the electrodes at a point extremely close to the ends of the envelope, which are made hemispherical, so that the zone back of the electrodes, which is the coolest part of the envelope, may be heated by the electrodes. With this new construction, which is contrary to the usual practice, I have found that it is essential that the metallic connection between the electrode and the inlead thereto should be relatively long with respect to the actual distance therebetween, in order to avoid excessive heat conduction thereto, both in the manufacture and in the operation of the device. The lower end of this envelope likewise tends to run at a somewhat lower

temperature than the upper end thereof, due to convection currents within the mercury vapor and in the air outside, but I have discovered that this can be overcome by coating the lower end of the envelope with an opaque substance which will conserve the radiant heat from the adjacent electrode. I have likewise found that where glass is used it is desirable to enclose the lamp envelope within an outer casing, which diminishes the 10 equal cooling effect of drafts, and which likewise diminishes the heat conduction therefrom, so that the desired operating temperature may be attained with a lesser expenditure of electrical energy. This outer casing is preferably filled with a 15 gas, such as nitrogen, at a pressure sufficient to prevent the production of a glow discharge between the lead wires to the lamp.

Due to the extremely high vapor density at which my novel lamp operates the discharge is 20 so constricted that it tends to tear to pieces any of the oxide coated cathodes heretofore proposed. I have found, however, that a hot, thermionic, cathode of novel design completely eliminates this difficulty and produces results not heretofore attainable. This new cathode of my invention is 25 so formed as to have an extremely small heat radiating surface in proportion to the electron emitting surface, a relatively low thermal capacity, and poor heat conduction from one part 30 thereof to another. I have discovered that a cathode having all of these novel characteristics can be conveniently produced by folding or rolling a piece of metal gauze into a compact mass, although any other metallic body having a similar 35 maze of internal passages may also be used. Exceptionally good results have been obtained using a cylindrical electrode of tightly rolled metal gauze having a small central opening. The total surface of such an electrode may be easily made 40 of the order of ten times the exterior, heat radiating, surface thereof, with the result that the heat loss from such an electrode per unit of active surface is extremely low. Hence little heat is needed to keep my novel electrode at an elevated 45 temperature. The thermal capacity of this novel electrode is likewise extremely low, as is also the heat conductivity thereof, due to the cellular structure. Both of these factors contribute materially to the rapid heating up of a cathode spot 50 at starting which is necessary to the long life of a cathode of this type, particularly in a lamp which must be frequently started, since the greatest damage is always done to such a cathode during those starting intervals when the necessary 55 electrons are obtained therefrom by the extremely destructive ionic bombardment thereof rather than by the desired thermionic emission. These intervals are greatly shortened by my novel structure. In the preferred embodiment the entire 60 gauze surface is coated with a good thermionic emitter, such as an alkaline earth oxide, and I have found that my novel structure affords unique advantages when thus coated. For example, I have found that my electrode, due to its 65 novel construction, is singularly immune to the flaking off of this active coating, which has heretofore been a serious obstacle to long cathode life. Furthermore, the very extensive interior surfaces of my novel cathode, in addition to contributing 70 a considerable amount of electron emission, likewise serve as a vast storehouse of the coating material, and I have found that there is a constant replacement by distillation from this storehouse of any material which may be sputtered off the 75 exterior surface, which thus remains activated

throughout the long life of the cathode. In this connection it is also to be noted that with my novel structure an unusually large proportion of the particles which may be sputtered off are intercepted by other parts of the cathode, and are thus available for further use, instead of being lost to the walls of the envelope. I have likewise found that the best results are to be attained when my novel cathode has an open bore of the order of 2 mm. in diameter. This open bore greatly facilitates the coating of the interior portion of the electrode, and likewise makes it possible to easily raise the temperature of the electrode by induction sufficiently to thoroughly degas it and to break down the alkaline compounds used in the 10 coatings. In addition to this, however, this open bore tends to attract the discharge at certain gas pressures, and thus to provide the beneficial effects of a cavity. The many points provided on the end of the electrode by the cut wires of the 20 gauze have likewise been found to be of advantage, the discharge invariably centering upon one of these points which runs so much hotter than the remainder of the electrode, due to the limited heat conduction, that when nickel is employed for 25 this gauze the point soon melts down into a little nodule on which the discharge continues to center. As a result of all of these effects I have found that my new electrode has an unusually long useful life, even under the conditions existing 30 in my novel high vapor density mercury arc lamp with its constricted arc discharge, although its use is obviously not limited to this particular type of discharge device, or to any particular gas or 35 vapor.

In any of these devices it is, of course, desirable that the discharge should start on the same potential as that on which it will efficiently operate. I have discovered that if a band or wire of 40 conducting material is placed around a critical part of the arc tube and connected to one of the electrodes the breakdown potential of the device is so much reduced that this is now commercially practicable for the first time.

While I have only mentioned mercury hereinbefore, this being the most commonly used metal vapor, it is obvious that other metals, such as 45 sodium, potassium, cadmium, thallium, and the like may also be used. For example, in a sodium lamp the efficiency has been found to be a maximum at a particular vapor density. My novel structure provides a means for constantly operating such a lamp at this desired density regardless of external conditions. Where vapor lamps 50 of any type are combined with incandescent lamps 55 for color correction or the like my novel structure is of particular advantage, for it eliminates the heretofore paramount problem of so ventilating the light unit as to maintain a predetermined temperature in the vapor device at all times. 60

For the purpose of illustrating my invention I have shown a preferred embodiment thereof in the accompanying drawing, in which

Fig. 1 is a perspective view of a mercury vapor lamp,

Fig. 2 is a sectional elevation of the arc tube employed in this lamp,

Fig. 3 is an elevational view, in part section, of a modification of the lamp of Fig. 1,

Fig. 4 is a perspective view of the electrode material before it is rolled up, and

Fig. 5 is an end view of an electrode, greatly enlarged.

As shown in this drawing, with particular reference to Figs. 1 and 2, a preferred form of my 75

mercury vapor arc lamp has a sealed tubular envelope 1 of any suitable vitreous material, such as glass. This envelope may be either transparent or translucent, as desired. For a 400 watt 5 lamp this envelope is conveniently made two inches in diameter and eleven inches long. A pair of inleads 2 and 3 extend through a re-entrant pinch seal at one end of said envelope, said inleads being connected to the tip and sleeve, respectively, of a conventional mogul base 4. A support wire 5 is likewise fused into said pinch 10 symmetrically with the inlead 3. Said inlead 3 and support wire 5 are each bent outwardly and carry at their outer ends the wires 6 and 7, respectively, which are of tungsten or any other material having the necessary rigidity. Said wires 6 and 7 extend parallel to the axis of the envelope 1 to a point near the opposite end thereof. Said wires 6 and 7 pass through two spaced 15 metal rings 8 and 9 which are suitably affixed thereto, as by welding or the like. A sealed tubular envelope 10 of suitable heat resisting vitreous material, such as "pyrex", "nonex", fused silica or the like, has hemispherical ends which 20 rest in said rings, whereby it is supported in a fixed position within the envelope 1. For a 400 watt lamp this envelope is about 7 inches long and $1\frac{1}{8}$ inches in diameter. The walls of this envelope are preferably of the order of a millimeter 25 thick, so that it has little heat capacity and thus warms up quickly, without danger of strains. The ring 9 has a mica ring 11 affixed thereto which snugly fits the inside of the envelope 1, whereby lateral support is provided for the free ends of 30 the wires 6 and 7. Said envelope 10 has an inlead 12, which is conveniently made of tungsten, sealed into each end thereof, each of said inleads terminating just inside of said envelope. A wire 13 of tungsten, molybdenum, or other metal of sufficient 35 rigidity, a 25 mil molybdenum wire being entirely satisfactory, is attached to the inner end of each of said inleads 12, each wire 13 being formed into a transverse loop of appreciable diameter and supporting at its free end an electrode 40 14, these electrodes being about 6 inches apart in a 400 watt lamp. The upper inlead 12 is joined to the inlead 2 by a flexible lead 18 which is conveniently formed of stranded soft nickel wire, while the lower inlead 12 is similarly connected 45 by a soft stranded wire 19 to the support wire 6. Several turns of wire 15 are closely wrapped about the envelope 10 at a point about a third of the way from the upper electrode 14 toward the lower electrode, this wire being electrically connected 50 to the wire 6, and thus to said lower electrode. The bottom of said envelope 10 about said electrode has a heat intercepting gold film 16 thereon, which may conveniently be applied in the form of a lacquer.

55 The inner envelope 10 has a filling of a rare gas, such as argon at a pressure of the order of 5 mm. of mercury, which constitutes the ionizable medium when the lamp is first started. An accurately measured quantity of the vaporizable metal, such as mercury, sodium, thallium, cadmium, or the like, is likewise sealed within this envelope. The amount of this metal is so chosen that it will all be evaporated when the coolest part of the envelope is at a desired temperature.

60 In a mercury vapor lamp it has been found that a vapor density corresponding to a temperature of the order of 360° C. is especially desirable for many purposes, hence the mercury is preferably so limited as to be completely vaporized when the 65 coolest part of the envelope is at this temperature.

If convenient the outer envelope 1 would be evacuated in order to minimize the heat conduction from the inner envelope 10, but in practice it is found to be impracticable to entirely degas the various metal parts therein, with the 6 result that residual gas evolves during operation of the lamp and supports an undesired glow discharge between the inleads 2 and 3. Accordingly, I prefer to fill the envelope 1 with a gas, such as nitrogen, at a pressure which is sufficient to 10 prevent the production of a glow discharge between these inleads. Thus in a 220 volt lamp I preferably use nitrogen at a pressure of approximately half an atmosphere.

The electrodes 14 are especially designed to 15 minimize the sputtering thereof, both during starting and during operation. As particularly shown in Figs. 4 and 5 these electrodes are preferably formed of metal gauze which is rolled up to form a cylindrical electrode having an open 20 bore. This electrode can be made of nickel, tungsten, molybdenum or the like, but in practice I have obtained extremely good results and long life using a gauze of seven mil nickel wire having 25 60 wires per inch parallel to the axis of the electrode and 40 in the other direction. In some cases, however, even better results are obtained with a composite gauze having the wires which are parallel to the axis of the electrode made of tungsten, molybdenum, or other refractory metal, 30 and the other wires formed of nickel, since this combines the easy activation of nickel with the more refractory property of the tungsten, the arc centering on the ends of the latter. The 35 gauze strips from which these electrodes are formed are approximately $\frac{1}{4}$ inch wide and aggregate $5\frac{1}{2}$ inches in length, the several pieces being welded together as shown in Fig. 4 to provide a simple means for attaching the inlead and for holding the end turn, as is clearly shown in 40 the drawing. With this construction there are obviously more than 325 small points provided by the ends of the various wires on which the discharge can center. The electrode likewise has an electron emitting surface of approximately 2.6 sq. 45 inches, although its effective heat radiating surface is only of the order of .3 sq. inch. After the electrode has been assembled as shown in Fig. 4 and attached to its inlead 12 it is carefully cleaned, as by hydrogen firing, and then dipped 50 in a water suspension of a mixture of barium carbonate and strontium carbonate, 15 grams of each of these in 100 c. c. of water having been found to produce the desired result. The porous or cellular nature of the electrode permits this suspension to penetrate every part thereof, this penetration being obviously assisted by the capillary action of the pores or cells. The central opening in the electrode likewise greatly facilitates this 55 penetration. After the electrodes have been suitably dried they are sealed into the envelope 10 in an obvious manner. Since electrodes so coated do not undergo any chemical change in air they may be stored as long as desired without any special 60 precautions, such as have necessarily been observed with the electrodes of the prior art.

The envelope 10 is then exhausted and thoroughly baked to drive out any occluded gas, after which the electrodes 14 are heated by induction to a temperature sufficient to break down the 70 carbonates to the oxide, the evolved gas being evacuated as produced. The loops 13 restrict heat flow from the electrodes 14 during this heating, of course, and thus both protect the seals, and make it easier to produce the necessary electrode tem- 75

perature. After this operation is complete a carefully measured quantity of mercury, 150 mg. in the case which has been described, is introduced within the envelope 10, together with a rare gas, 5 argon at a pressure of the order of 5 mm. of mercury being preferred. The envelope 10 is then sealed off, after which it is placed in the envelope 1 in the manner which has been shown and described.

10 My novel device, when constructed as described, will start when an alternating current potential of 150 volts is applied thereto. This relatively low breakdown potential is the result of several factors. In the first place the wire 6, due to its 15 proximity to the envelope 10, is effective to some extent to reduce the potential necessary to start the discharge, due to the fact that it is connected to one of the electrodes 14. The presence of the encompassing wire 15, however, greatly increases 20 this effect if this wire is located at a critical point which is approximately two-thirds of the distance from the electrode 14 to which it is connected toward the other electrode, although this wire 15 will be of value if located anywhere between 25 a quarter and a half of the way toward the electrode to which it is connected. A single turn of said wire 15 at the exact critical point would be sufficient to produce the major part of this reduction in breakdown voltage, but by providing 30 several turns thereof the effect is slightly enhanced, and at the same time the exact position of the edges thereof becomes less critical, so that the device may be more readily produced by mass production methods. The numerous points on 35 the electrodes 14 are likewise believed to concentrate the static field, since they facilitate the necessary ionization of the gas, with a consequent further reduction in the breakdown potential of the device. The active coating on these electrodes likewise enhances this result.

At the instant of starting the entire emission from the cathode is produced, of course, by 40 ionic bombardment thereof, due to the fact that it is cold. Since this type of emission is extremely destructive of an electrode it is obvious 45 that it is essential that the heating period of the electrode, during which the thermionic emission thereof is increasing until it is adequate to support the discharge, should be as short as possible. I have found that this result is attained 50 by my novel electrode, for there is obviously but little heat conduction from the wire tip on which the "hot spot" concentrates at starting, and this tip likewise has but little thermal capacity, with the observed result that this spot almost instantly 55 reaches the requisite temperature to support the discharge by thermionic emission. Likewise, due to this same low heat conduction the remainder of the electrode remains relatively cool, so that there is little tendency for the discharge to shift 60 from this hot wire tip to another one, which would then have to go through a brief period of ionic bombardment, although it is apparent that the entire surface of the electrode, internal as 65 well as external, contributes to the electron emission therefrom. It has been observed that the discharge, which is very constricted in my high pressure mercury arc lamp, centers upon a single point for long intervals, melting the nickel 70 wire tips down into little nodules, although at lower pressures the discharge tends to spread more uniformly over the electrode. The remainder of the electrode is sufficiently heated, however, to give some emission and also to keep 75 these points activated with the barium and

strontium coatings, the interior of the electrode serving as a vast storehouse of this active material. As a result my novel electrodes have been operated for thousands of hours, even under extremely unfavorable conditions, without 5 losing any of their desirable characteristics.

Like all gaseous discharge devices my novel lamp has a negative volt ampere characteristic. Hence as indicated in Fig. 1 my lamp is ordinarily operated in series with a suitable inductance on 220 volts A. C. This inductance causes the lamp current to lag behind the line voltage and thus continues the light on one half cycle until a favorable moment for the initiation of a reverse discharge on the next half cycle. 15 As a result the usual flicker observable with alternating current discharge lamps is virtually eliminated, due to the unusually short dark interval. For best results the iron of the inductance should not be saturated by the maximum 20 current drawn, a reactor having an air gap being preferred, since a saturable reactor tends both to peak the current, causing a noticeable flicker, and to so limit the current at the beginning 25 of the cycle as to render the arc unstable.

When the arc is first started it is, of course, virtually a pure argon discharge, but as the temperature rises the mercury vapor density increases, and the arc becomes virtually a pure 30 mercury vapor discharge. This vapor density continues to increase with the temperature, with a corresponding change in the arc voltage, until the mercury is completely vaporized. A further increase in temperature will then merely 35 superheat this vapor and the electrical characteristics thereafter are those of a fixed gas. I prefer to operate my device with a considerable amount of superheat, since then a decrease in ambient temperature or line voltage will not change either the vapor density or the arc voltage. 40 Thus my novel device will operate with an arc voltage of the order of 160 volts with a current of 2.8 amperes, regardless of reasonable variations in ambient temperature. This makes 45 my novel lamp especially suitable for street and other outdoor lighting, where the extreme variations in temperature have made it impracticable to operate a mercury vapor arc heretofore. It likewise is of advantage where my novel lamp is combined in a single fixture with incandescent 50 lamps, for the heat of the incandescent lamps will have virtually no effect upon the operation 55 of the vapor arc. When operated under the above conditions my novel lamp has a total output of approximately 14,000 lumens, this being about 35 lumens per watt.

By making the lamp smaller in diameter and operating with the same arc current and voltage the outer envelope may be eliminated, but in this case it is usually necessary to make the envelope 60 of fused silica, fused fluorite, or one of the harder glasses, intermediate between "pyrex" and fused silica, in order to withstand the higher temperatures which must be developed to insure freedom from mercury condensation due to 65 drafts or the like. The ultraviolet emission of such a lamp is often desirable, however, and hence such a construction, using fused silica, fluorite, or the like, is preferred in some cases. Such a lamp, of course, retains all the advantages of self-starting and stable and high efficiency operation which have been heretofore described. A construction which has been found to give good results in this type of lamp is shown in Fig. 3. In this lamp, which is de- 70 75 75

signed to operate with the same arc voltage and current as the lamp of Fig. 1, the lamp envelope 21 is made of fused silica tubing having an inside diameter of approximately $\frac{1}{8}$ of an inch. The electrodes 14, which are approximately 6 inches apart, are supported by the inleads 12 close to each end of said envelope, being attached thereto through transverse loops 13, as in Fig. 1. Said inleads are each sealed 10 into said envelope 21 through an external graded seal 22. An asbestos tube 23 is placed about each of said seals in order to maintain the temperature thereof, and in addition a heater 24 is preferably coiled thereabout. Said heater conveniently comprises about 10 or 12 turns of #21 15 nichrome wire, or enough of any other resistance wire to give approximately 1 ohm resistance. One end of said heater 24 is connected to the adjacent inlead 12, while the other end thereof is connected to a combined terminal and 20 guard 25 which is attached to the end of said envelope 21 in a well known manner. An annular baffle 26 is fused to the wall of said envelope 21 at a point slightly above the lower electrode 25 14, said baffle having an opening of approximately $\frac{1}{8}$ of an inch therethrough. A wire 27 is wound about the arc tube 21 for about an inch at a point approximately a third of the distance from one electrode 14, said wire being connected 30 to the terminal 25 which is the more remote therefrom. Said envelope 21 is filled with argon at a pressure of the order of 5 mm. of mercury and contains a quantity of mercury, about 35 mg., which will all be vaporized at the same temperature as that in the lamp of Fig. 1.

The lamp of Fig. 3 will start and operate, in series with a stabilizing inductance, on 220 volts A. C. with substantially the same characteristics as the lamp of Fig. 1, the baffle 26 causing but little change in either the starting or operating potential. The absence of the outer envelope is, of course, compensated for by the smaller heat radiating surface, this lamp operating at a temperature considerably in excess of that of Fig. 1 in order to insure continuous operation in the superheated range despite drafts and the like. The asbestos tube 23 and the series heater 24 cause each graded seal 22 to be maintained at the requisite temperature to prevent mercury condensation therein, despite the distance thereof from the discharge, while the baffle 26 breaks up the convection currents and thus causes a greater proportion of heat to be retained about the lower electrode 14, so that it will operate at substantially the same temperature as the upper electrode 14. In addition said shield 26 reduces the blackening of the arc tube by particles sputtered from the lower electrode. This lamp has been found to be an extremely efficient ultraviolet generator, and is useful for various therapeutic and photo-chemical purposes.

While I have described my invention by reference to specific embodiments thereof, it is to be understood that various changes, substitutions, or omissions, within the scope of the appended claims, may be made therein without departing from the spirit of my invention.

I claim as my invention:

1. An electric gaseous discharge device comprising a sealed tubular envelope of vitreous material, an electrode sealed into each end thereof, a vaporizable material within said envelope in an amount which is less than that necessary to saturate the space within said envelope at the normal operating temperature of said device, a heat trap

adjacent the lower end only of said envelope to reduce the heat losses therefrom to overcome the unequal cooling effect of convection currents on opposite ends of said device, and electrical connections for supplying sufficient energy to said device to raise it to said temperature. 5

2. An electric gaseous discharge device comprising a sealed tubular envelope of vitreous material, an electrode sealed into each end thereof, a vaporizable material within said envelope in 10 an amount which is less than that necessary to saturate the space within said envelope at the normal operating temperature of said device, an annular baffle within said envelope close to the lower electrode to increase the amount of heat 15 retained at the lower end of said envelope, and electrical connections for supplying sufficient energy to said device to raise it to said temperature.

3. An electric gaseous discharge device comprising a sealed tubular envelope of vitreous material, an inlead sealed into each end thereof, an electrode consisting of a plurality of contiguous layers of metal gauze almost in contact with each end of said envelope, said gauze being coated throughout with an alkaline oxide, a connection 20 between each inlead and the adjacent electrode which is longer than the distance therebetween whereby heat conduction to said inleads is minimized, a vaporizable material within said envelope and a conducting band having at least one complete turn about said envelope at a point which is substantially a third 25 of the way from one electrode toward the other, said band being electrically connected to the latter electrode. 30

4. An electric gaseous discharge device comprising a sealed tubular envelope of vitreous material, an inlead sealed into each end thereof, an electrode almost in contact with each end of said envelope, said electrode being coated with an alkaline oxide, a connection between each inlead 40 and the adjacent electrode which is longer than the distance therebetween whereby heat conduction to said inleads is minimized, a vaporizable material within said envelope, a conducting band having at least one complete turn about said envelope at a point which is substantially a third 45 of the way from one electrode toward the other, said band being electrically connected to the latter electrode, and a heat intercepting coating on one end only of said envelope about the inlead. 50

5. An electric gaseous discharge device comprising a sealed tubular envelope of vitreous material, an inlead sealed into each end thereof, an electrode almost in contact with each end of said envelope, said electrode being coated with 55 an alkaline oxide, a connection between each inlead and the adjacent electrode which is longer than the distance therebetween whereby heat conduction to said inleads is minimized, a vaporizable material within said envelope, a conducting band having at least one complete turn about said envelope at a point which is substantially a third 60 of the way from one electrode toward the other, said band being electrically connected to the latter electrode, and an electrical resistance heater 65 about the inlead seals to prevent vapor condensation therein.

6. A gaseous electric discharge device comprising a tubular sealed envelope, a gaseous atmosphere therein, electrodes sealed into said envelope at opposite ends thereof, and an electrically conductive band having at least one complete turn about said envelope at a point substantially one third of the distance from one electrode toward 75

- another, said band being electrically connected with the more remote of said electrodes.
7. An electric gaseous discharge device comprising a tubular sealed envelope, a gaseous atmosphere therein, electrodes sealed into said envelope at opposite ends thereof, an electrical conductor extending along the surface of said envelope from a point adjacent to one of said electrodes to a point two thirds of the distance toward the other of said electrodes, said conductor being connected to the first of said electrodes, the free end of said conductor terminating in a conductive band which encompasses said envelope.
- 15 8. In a gaseous discharge device, a cathode consisting of a metal body having a maze of internal passages whereby the total surface of said body is several fold the exterior heat radiating surface thereof, the entire surface of said body including that of the internal passages being coated with a substance having a high thermionic emission which is thin enough to not close said passages.
9. In a gaseous discharge device, a cathode consisting of a body of metal gauze having a plurality of contiguous layers of said gauze, the total surface of said gauze being at least several fold the exterior heat radiating surface of said body, the wires forming said gauze being coated throughout said body with a substance having a high thermionic emission which does not close the interstices within said body.
10. In a gaseous discharge device, a cathode consisting of a body of metal gauze having a plurality of contiguous layers of said gauze, the wires forming said gauze being coated throughout said body with an alkaline earth oxide, the cut ends of
- said wires being exposed on at least one surface of said body.
11. In a gaseous discharge device, a cathode consisting of a roll of metal gauze having a plurality of contiguous turns and an open bore of the order of two millimeters in diameter, the wires forming said gauze being coated throughout said roll with an alkaline earth oxide, the cut ends of said wires being exposed at the end of said roll.
12. In a gaseous discharge device, a cathode consisting of metal gauze, a portion of the wires of said gauze consisting of nickel while the remainder of said wires consists of a more refractory metal, said wires being coated with a substance having a high thermionic emission.
13. In a gaseous discharge device, a cathode consisting of a body of metal gauze having a plurality of contiguous layers of said gauze, part of the wires forming said gauze consisting of nickel while the remainder consists of a more refractory metal, the cut ends of the latter wires being exposed on at least one surface of said body, said wires being coated throughout with an alkaline earth oxide.
14. In a gaseous discharge device, a cathode consisting of a roll of metal gauze having a plurality of contiguous turns, the wires of said gauze which extend around the axis of said roll consisting of nickel while the wires parallel to said axis consist of a more refractory metal, the cut ends of the latter wires being exposed at one end of said roll, all of said wires being coated throughout said roll with a substance having a high thermionic emission.

JAMES A. ST. LOUIS.
